UNITED STATES PATENT OFFICE.

CHARLES GUISCHARD, OF RICHMOND HILL, NEW YORK.

CONVEYER TOY.

Application filed October 8, 1925. Serial No. 61,185.

To all whom it may concern:

Be it known that I, CHARLES GUISCHARD, a citizen of the United States, residing at Richmond Hill, in the county of Queens and 5 State of New York, have invented certain new and useful Improvements in Conveyer Toys, of which the following is a specification.

The main object of this invention is to 10 provide a conveyer used as a toy and having for its essential characteristics the construction of a cable spanned between two points distant from one another and is adapted to be shifted by tautening of the cable. The 15 cable serves as a guideway for a suspended bucket and is adapted thru the construction of the toy to cause the suspended bucket to travel to and fro, this travel being accomplished by inclining and declining the cable 20 when the bucket has reached the lowest level at the end of its travel.

Another object is to provide a toy conveyer having a spanned cable and a bucket suspended from said cable which is adapted 25 to move to and fro and at one end of its travel, a mechanism is provided for tilting the bucket to empty it of its contents.

Referring briefly to the drawings, Figure 1 is a side elevational view of the toy, 30 showing the spanned cable at its normal angle of declination.

Figure 2 is a view similar to Figure 1, 35 showing the spanned cable at an angle of inclination and illustrating the method of dumping the bucket.

Figure 3 is a top plan view of Figure 1.

Referring in detail to the drawing, the numeral 10 indicates the base upon which the entire structure of the toy is mounted. 40 At one end of the base, a pier 11 extends upwardly and is propped by a brace 12. Extending upwardly from the upper end of the pier is a flexible staff 13 which is provided with a stop knob 14 at its upper end. 45 A yoke member 15 passes around the sides of the staff and the arms 16 of the yoke have a stud 17 mounted therein on which a grooved guide roller 18 is mounted. A weight 19 is provided on the bottom of the 50 yoke member where the arms join and is adapted to normally cause the entire yoke member to ride downwardly on the periphery of the staff 13, the roller 18 being the member that contacts with the staff. An eyelet 20 is fixed to one end of the yoke 55 15 and is secured thereto a flexible cable 21.

This flexible cable extends across the base from the yoke 15 normally at an angle of inclination and is paid about the grooved pulley 22, which is supported in ears 23, the 60 ears being fixed to a post 24 positioned at the opposite end of the base 10. The flexible cable 21 is paid a quarter turn about the pulley 22 and then courses downwardly as shown at 25, being paid at the lower position a quarter turn around a pulley 26 and then passes again to the pier 11. At a convenient position on the pier, a stud 27 is 65 fixed. On the stud, a hand wheel 28 is rotatably mounted. This hand wheel is provided with a hub 29 and extending radially from the hub is an arm 30 to whose outer end, a returning length 31 of the cable is secured. On the periphery of the wheel 28, 70 a pair of grooves are formed. These grooves, indicated by the numeral 31, are cooperated with by a resilient arm 32 which is fixed to the side of the base 10, the arm 75 when in one of the grooves serving as a stop to prevent a hand wheel from being rotated 80 inadvertently.

On the end 21 of the flexible cable, a grooved roller or pulley 32 is seated and pivotally suspended from this roller are a pair of straps 33 and 34 from which an inverted triangular bucket 35 hangs pivotally suspended. A hopper 36 having a funnel 37 at its lower end, is mounted on the base 10 opposite to the pier 11 and from the forward or end nearest the pier, a dumping 90 ledge 38 extends upwardly. The upper edge of this dumping ledge is adapted to be engaged by a downwardly extending ear 39 formed at the junction of the sides of the bucket 35 and causes tilting of said bucket 95 when so engaged.

The toy is constructed to form an entertaining and educational toy for children. When the staff is in normal upright position, the upper length of the flexible cable 100 21 is at an angle of declination, that is, being lower near the pier and higher near the post 24. In this position, the pulley 22 rests approximately in the position as shown in Figure 1. In order to cause the 105 bucket and the entire apparatus suspended from the pulley 32 to ride in the opposite direction, it is necessary to incline this end of the cable 21. The inclination of the cable length 21 from the pier 11 downwardly is accomplished by rotating the hand wheel 28 by manipulating and grasping the 110

knob 40. Rotating this knob in a counter-clockwise direction 90 degrees, likewise rotates the arm 30 from the vertical to a horizontal position, thus pulling upon the entire length of flexible cable. In pulling on this flexible cable, the flexible staff 13 is deflected to one side toward the post 24, as indicated in Figure 2. As the staff is deflected, the pulley 18 rides upwardly upon the periphery of the staff 13 to an inclined position shown in Figure 2, when the yoke 15 and pulley 18 rides upwardly on the staff and the cable length 21 begins to incline from the pier downwardly, the bucket conveyer 35 begins to roll toward the opposite end of the base 10 and gains momentum until the cable arrives at its final degree of inclination. When the bucket 35, suspended from the pulley 32, nears the hopper 36, the ear 39 on the bucket 35 engages the ledge 38 and causes said bucket to tilt until its contents are emptied into the hopper 36. When this operation has been completed, the hand wheel again is rotated, but in an opposite, a clockwise direction, which permits lengthening of the cable end 21 and allows the staff to resume its vertical position, as shown in Figure 1, the length of cable 21 thereafter again finding itself at an angle of declination, at which the suspended bucket rides from the position adjacent the hopper to the opposite end of the base toward the pier 11.

I claim:—

1. A toy conveyer comprising a base, a vertical and flexible staff extending from one end of said base, a rigid post at the opposite end of said base, a carriage adapted

to ride vertically on said staff comprising a yoke, a pulley mounted rotatably in said yoke, a cable fixed to the yoke and spanning the distance between the post and staff, and means connected to said cable for deflecting the staff to incline said cable.

2. In a toy conveyer, a base, a flexible staff extending upwardly from one end of said base, a rigid post extending vertically from the opposite end of said base, a wheeled carriage adapted to ride vertically on said staff, said carriage comprising a yoke adapted to pass around said staff, a pulley rotatably mounted between said yoke and adapted to ride upon the surface of said staff, a cable fixed to said pulley extending horizontally toward the rigid post, said cable being adapted to have one end lifted or lowered by raising or lowering said yoke, said cable when pulled being adapted to deflect the staff to raise said cable to an angular position, and means for pulling said cable.

3. In a toy conveyer, a base, a vertical rigid post at one end of said base, a tapering flexible staff mounted on said base opposite to the post, a yoke, a grooved pulley on said yoke adapted to ride upwardly or downwardly on said staff, a weight integral with said yoke being adapted to cause the yoke and pulley to ride downwardly on the staff when the latter is vertical, a cable stretched between said post and yoke, said cable when pulled being adapted to flex the staff toward the post and cause the yoke to ride upwardly upon the flexed staff to incline said cable.

In testimony whereof I affix my signature.
CHARLES GUISCHARD.
